UNITED STATES PATENT OFFICE

HARRY M. EPSTEIN, OF NEW YORK, N. Y.

GLIDER

Application filed June 10, 1927. Serial No. 197,776.

My invention relates particularly to gliders adapted to be applied to furniture to support the same.

The object of my invention is to provide gliders of an improved type, adapted to be applied to portions of furniture for the support of the same, and which are adapted to support the furniture while eliminating noise to a maximum extent when moving the furniture from place to place. Gliders made in accordance with my invention are capable of being applied to any portion of any kind of furniture to support the same, but are applicable especially to the legs or feet of chairs, tables, settees, etc.

Hitherto gliders provided for supporting furniture have had many disadvantages. As originally made, such gliders were comprised merely of a large metal head having a stem 5 adapted to be driven into the furniture at the point of support and with no means whatever for absorbing shocks between the furniture and the glider. As a result, in such construction, the movement of the furniture over 10 floors, and particularly in the case of very hard floors, such as those made of marble, stone, concrete, etc., caused a great deal of noise. This is a very undesirable effect, especially in the case of large rooms or halls 15 where a large number of chairs are being moved at a given time, as will be readily understood. Attempts have been made at the time to absorb all shocks between the gliders and the furniture but in those constructions 20 a number of disadvantages have developed. Such previous constructions have had such a tight union between the glider and the article of furniture as to transmit a considerable amount of noise under certain circumstances when moving the furniture. Furthermore, in some instances the construction 25 was such as not to effectively hold the glider cap, which contacts with the floor securely in position so that such caps oftentimes became dislodged and destroyed the effectiveness of the glider. Also, the holding means for such caps, in certain instances, were soft and ineffective, tending to produce the undesirable result just mentioned. In other instances, in previous constructions, in the en-

deavor to secure the cap tightly in place it has been found necessary to make the cap of comparatively soft metal so as to permit the edges of the same to be drawn over for clamping the cap in position. The result of this has been to cause the cap to wear out readily, thus producing great friction with the floor and consequent difficulty in enabling the furniture to be moved. Also, such soft metal constructions have been found to make decided marks on some floor-coverings, such, for example, as linoleum. Furthermore, in the effort to hold such caps in place it has been found that the material contained therein has become packed so tightly as to prevent a 55 resiliency such as is necessary to prevent the making of unnecessary noises when moving the furniture.

The object of my invention is, therefore, to avoid these difficulties. Especially, it is one of my objects to hold the stem in permanent union with the cap but with a loose connection thereto so as to provide an amount of free play between the stem attached to the furniture and the cap secured thereto, so as 60 to enable a maximum resiliency to be obtained by reason of the interposed body of resilient material located between the furniture and the cap supporting the same. A further object is to permit in this manner, not only a resiliency in a vertical direction between the furniture and the cap, but in a lateral direction as well. A resiliency in the lateral direction is important as it has been found that shocks which might be transmitted laterally between the glider and the furniture in sliding the latter over the floor, have very distinct vertical components which produce a considerable amount of noise unless an effective cushioning means is provided to take up the lateral shocks, as has been done in the gliders made in accordance with my invention. Further objects of my invention will appear from the detailed description of the same hereinafter.

While my invention is capable of embodiment in many different forms, for the purpose of illustration I have shown certain forms of the same in the accompanying drawings, in which—

Figure 1 is a side elevation of one embodiment of my invention in which a coil spring is used for connecting the stem to the cap;

Figure 2 is a vertical section of the same;

Figure 3 is a plan view of the coil spring used therein;

Figure 4 is a perspective view of a modified form of my invention;

Figure 5 is a vertical section through the same;

Figure 6 is a vertical section at right-angles to the section in Figure 5;

Figure 7 is a plan view of the ring for holding the stem in place in the cap; and

Figure 8 shows another way of applying the glider to a chair;

Referring first to the form of my invention shown in Figures 1 to 3, I have provided a glider comprising a cap 1 in which there is contained a coil-spring 2, the central portion of which provides an opening 3 in which there is loosely carried a stem 4 having a head 5. It will be noted that the opening 3 is such as to allow a certain amount of play between the stem 4 and the coil-spring 2 in a lateral direction. If desired, between the head 5 and the cap 1 there may be provided a fabric or paper disk 6 in order to support the movable parts of the spring and head 5 from the metal cap 1. Above the cap 1 and on the stem 4 I provide a washer 7 of resilient material, such, for example, as rubber. It will thus be seen that when the stem 4 is driven into the end of a leg 8 of a chair, for example, the chair will rest upon the rubber-washer 7, which will become forced slightly into the opening at the top of the cap 1. The leg 8 of the chair thus becomes cushioned, not only in a vertical direction but, also, in a lateral direction, owing to the free play between the stem 4 and the spring 2, and, also, because of the lateral movability of the inner coils of the spring 2 with regard to the cap 1. It will be seen that, as in Figure 2, the glider may be driven in only so far as to leave the head 5 in contact with the disk 6, or it may be driven farther so as to have the cap 1 pushed back after driving from the head 5 by the force of the rubber, as shown in Figure 8.

In the other form of my invention shown in Figures 4 to 7, the construction is just the same except that in this instance, instead of the spring 2 I have provided a ring 9 having a radially directed extension 10 toward the center of the ring, carrying on its inner end a similar ring 11 in which is loosely received the stem 4. It will be understood that in this instance, also, the ring 9 acts largely as a spring to permit lateral movement between the ring 11 and the cap 1, in addition to the lateral movement which is possible between the stem and the ring 11.

In the operation of my invention, referring first to the form of my invention shown in Figures 1 to 3, it will be understood that the

glider is attached to the furniture, as, for example, the leg of the chair 8, by driving the stem 4 into the same, the spring 2 being formed to press at its center against the inside of the cap so as to hold the head 5 against the cap 1. This can be done either with the parts assembled or with the cap removed followed by the final application of the cap 1 to the remainder of the construction. However, it is preferably to apply the glider to the furniture in completely assembled form, especially as it is desired to have the rubber washer 7 more or less tightly clamped between the cap 1 and the leg 8 of the chair. This is for the purpose, as pointed out above, of causing the furniture to become supported firmly from the cap 1, which is in turn supported from the floor, and, also, so as to provide a firm position for the furniture which is cushioned, not only in a vertical direction from the cap 1, but, also, in a lateral direction due both to the loose connection between the stem 4 and the cap 1, and between the inner coils of the spring 2 with regard to the cap 1.

When the article of furniture, as, for example, a chair, is being slide over a floor, it will be seen that there is an effective cushioning between the furniture and the cap 1, due to the rubber washer 7, thus eliminating noise which would otherwise result. Also, for the reasons just explained, any tendency of the cap 1 to resist movement laterally and thus produce noise, will be compensated for by reason of the cushioning effect between the cap 1 and the leg 8 of the chair. This is very important as it has been found that such lateral resistance on the part of movement of the cap produces vertical component, resulting in a great deal of noise unless the construction is such as to eliminate the same.

In the other form of my invention, as shown in Figures 4 to 7, the operation is just the same except that in this instance the ring 9 coupled with the inner ring 11, which provides a loose connection with the stem 4, enables the desired lateral cushioning effect to be attained in a similar manner.

While I have described my invention above in detail I wish it to be understood that many changes may be made therein without departing from the spirit of the same.

I claim:

1. A glider having a cap, a stem, a bent wire forming the connecting means for connecting the cap to the stem, and a cushioning means adapted to support the cap from the furniture to which the glider is adapted to be attached.

2. A glider having a cap, a stem, a bent wire for providing a laterally loose connection between the cap and the stem, and a cushioning means adapted to support the cap from the furniture to which the glider is adapted to be attached.

3. A glider having a cap, a stem, a wire coil spring for providing a laterally loose connection between the cap and the stem, and a cushioning means adapted to support the cap from the furniture to which the glider is adapted to be attached.
4. A glider having a cap, a stem, a bent wire forming the connecting means for connecting the cap at its edge to the stem, and a rubber washer adapted to support the cap from the furniture to which the glider is adapted to be attached.
- 10 5. A glider having a cap, a headed stem, a bent wire forming the connecting means for connecting the cap to the stem, a rubber washer adapted to support the cap from the furniture to which the glider is adapted to be attached, and a fabric disk located between the headed stem and the cap.
- 15 6. A glider having a cap, a headed stem, means for providing a laterally loose metallic connection between the cap and the stem, a rubber washer adapted to support the cap from the furniture to which the glider is adapted to be attached, and a fabric disk located between the headed stem and the cap.
- 20 7. A glider having a cap, a headed stem, a bent wire for providing a laterally loose metallic connection between the cap and the stem, a rubber washer adapted to support the cap from the furniture to which the glider is adapted to be attached, and a fabric disk located between the headed stem and the cap.
- 25 8. A glider having a cap, a headed stem, a wire coil spring for providing a laterally loose connection between the cap and the stem, a rubber washer adapted to support the cap from the furniture to which the glider is adapted to be attached, and a fabric disk located between the headed stem and the cap.
- 30 40 In testimony that I claim the foregoing, I have hereunto set my hand this 3rd day of June, 1927.

HARRY M. EPSTEIN.

CERTIFICATE OF CORRECTION.

Patent No. 1,733,725.

Granted October 29, 1929, to

HARRY M. EPSTEIN.

It is hereby certified that error appears in the printed specification of the above numbered patent requiring correction as follows: Page 2, line 75, for the word "preferably" read "preferable", and line 92, for "slide" read "slid"; page 3, line 9, claim 4, strike out the words "at its edge" and insert the same to follow after the word "cap" in line 10, same claim; and that the said Letters Patent should be read with these corrections therein that the same may conform to the record of the case in the Patent Office.

Signed and sealed this 3rd day of December, A. D. 1929.

(Seal)

M. J. Moore,
Acting Commissioner of Patents.
